Primary Examiner — Richard E Chilcot*(74) Attorney, Agent, or Firm* — Cionca IP Law P.C.;
Marin Cionca(57) **CLAIM**

The ornamental design for a casing cover for pump, as shown and described.

DESCRIPTION

FIG. 1 is a front, top perspective view of a casing cover for pump showing the new design;

FIG. 2 is a rear, top perspective view thereof;

FIG. 3 is a front, bottom perspective view thereof;

FIG. 4 is a rear, bottom perspective view thereof;

FIG. 5 is a front, top plan view thereof; and,

FIG. 6 is a front, bottom plan view thereof.

The broken lines and unshaded surfaces bounded by broken lines form no part of the claimed design.
